UNITED STATES PATENT OFFICE.

OSCAR F. FORSBERG, OF YONKERS, NEW YORK, ASSIGNOR TO WESTERN ELECTRIC COMPANY, INCORPORATED, OF NEW YORK, N. Y., A CORPORATION OF NEW YORK.

ADJUSTABLE MOUNTING FOR TERMINAL-BANK PANELS.

Application filed December 4, 1919. Serial No. 342,377.

To all whom it may concern:

Be it known that I, OSCAR F. FORSBERG, a citizen of the United States, residing at Yonkers, in the county of Westchester, State 5 of New York, have invented certain new and useful Improvements in Adjustable Mountings for Terminal-Bank Panels, of which the following is a full, clear, concise, and exact description.

10 This invention relates to automatic switches employed to interconnect telephone lines and more particularly to switches of the panel type. Its object is the provision of an adjustable mounting whereby a panel can be 15 adjusted in all directions to the end that the contact terminals on the face of said panel can be brought into proper alignment with their respective contact brushes.

In a multiple brush selector switch, for 20 example, such as that described in U. S. Patent 1,123,799 to John N. Reynolds, there are employed a number of terminal bank panels arranged in superposed relation to each other and vertically operated contact 25 brushes cooperating with the terminals on the faces of the panels. It is important that these terminals be in proper alignment with their respective contact brushes as any appreciable misalignment is likely to result in 30 poor contacts. Due to inevitable manufacturing variations it has been found difficult in many instances to secure proper alignment when the panels are rigidly attached to a supporting frame without suitable provisions 35 whereby the panels can be readily adjusted so that the terminals will line up with the brushes.

In accordance with the above object, this 40 invention provides a simple and convenient means whereby terminal bank panels can be adjusted in all directions.

This invention is best described by reference to the drawing, in which Fig. 1 is a fragmentary front elevation of three panels 45 with adjustable mountings and a supporting structure therefor. Fig. 2 is a fragmentary perspective view showing two panels and the mounting arrangement whereby the panels are adjusted, and Fig. 3 is a perspective 50 detail of a supporting member for the panels.

In Figs. 1 and 2, 1, 2 and 3 are panels comprising layers of terminal strips extending horizontally across the panels and insulated from each other. Each terminal

strip has a terminal for each of the vertical "group rows" and, therefore, each vertical "group row" is a duplicate of and is multiplied with all the other vertical "group rows" of the same panel. For each vertical "group row" a set of contact brushes (not shown) and a mechanism for moving these brushes up and down so as to pick out predetermined groups of terminals 15, 16 and 17, is provided. When these contact brushes 60 are not busy they rest at the bottom of their respective group rows and are held in alignment therewith by the teeth 18, 19 and 20 of the die cast comb 21.

A steel structure is provided for supporting the panels and the latter are adustably mounted on this structure by means of the horizontal screws 5 and vertical screws 6. Screws 5 engage the lugs 8 and 9 of the supporting member 4 by the apertures 13 70 and 14 and are held in place therein by nuts 10 and 11 and engage apertures at points 12 in the frames of the panels. The panels are adjustable horizontally by means of screws 5 and nuts 10 and 11. Screws 6 engage the 75 frames of the panels and bear on cross member 7 of the supporting structure and the panels are vertically adjustable thereby. The apertures at points 12 in the frames of the panels are made appreciably larger than the engaging diameter of the screws 5 and thus provide means whereby the panels can be adjusted both vertically and horizontally 80 in a plane parallel to their faces. It will be seen then that screws 5 and 6 and the apertures at points 12 provide means whereby the panels can be readily adjusted in all directions. 85

Supporting member 4 embodies the unique 90 and economical feature of providing two lugs for screws 5, thus obviating the necessity of providing and attaching two supporting lug members at those points where two panels join, as shown in Fig. 2.

What is claimed is:

1. In combination with a terminal bank, a supporting structure therefor, and horizontal and vertical screws, each associated with said bank and said supporting structure jointly, said terminal bank adapted 105 to be moved horizontally and vertically through the adjustment of said horizontal and vertical screws respectively.

2. In combination with a terminal bank and a supporting structure therefor, a lug 110

attached to said supporting structure, a horizontal screw attached to said lug and to said bank, and cooperating therewith to provide horizontal adjustment for said bank and a

5 vertical screw attached to said bank bearing on said supporting structure and providing vertical adjustment for said bank.

3. In combination with a terminal bank and a supporting structure therefor, a lug 10 attached to said supporting structure, a horizontal screw attached to said lug and engaging an aperture in the frame of said bank, said aperture being, in diameter, appreciably larger than the engaging diameter 15 of said horizontal screw member; a vertical screw attached to said bank and bearing on said supporting structure, said horizontal and vertical screws together with said aperture in frame of said bank affording 20 adjustment for said bank in all directions.

4. In combination, a supporting structure, two terminal bank panels supported by said structure in superposed relation one to the other, a double lug supporting member attached to said structure, and two horizontal 25

adjusting screws, each associated jointly with said member and one of said panels, and adapted to provide horizontal adjustment for said panels.

5. In combination, two terminal bank 30 panels in superposed relation, a supporting structure for said panels, a double lug supporting member for said panels attached to said supporting structure, horizontal screws providing forward and back adjustment for 35 said panels, each secured jointly to one of the lugs of said supporting member and to one of said panels, and each extending through an aperture in its respectively associated panel, said aperture being larger 40 than the portion of said screw which passes therethrough, thereby providing lateral adjustment for said panels, and a vertical screw jointly engaging said panel and said supporting structure, whereby said panel 45 may be adjusted vertically.

In witness whereof, I hereunto subscribe my name this 1st day of December, A. D., 1919.

OSCAR F. FORSBERG.
